By Cheever & Cox Attn:

UNITED STATES PATENT OFFICE.

RAYMOND B. DWYER, OF CHICAGO, ILLINOIS.

DRAPERY HANGER.

Application filed December 30, 1921. Serial No. 526,019.

To all whom it may concern:

Be it known that I, RAYMOND B. DWYER, a citizen of the United States, residing at Chicago, in the county of Cook and State 5 of Illinois, have invented a certain new and useful Improvement in Drapery Hangers, of which the following is a specification.

My invention relates to drapery hangers, and one of the objects of the invention is to 10 provide a self-acting hanger so constructed that the drapery when in place will conceal the pole. Another object is to provide a hanger of this type by the use of which the pole will be concealed whether the drapery 15 is single or double. Another object is to provide a hanger of this pole-concealing type which will dispense with the need of sewing. Still another object is to provide means for readily obtaining a "French 20 plait." Another object is to produce a hanger which is self intensifying or compensating so that the heavier the drapery the tighter will be the gripping action. Still another object is to provide a construction 25 which will enable the hanger to slide easily without the aid of antifriction rollers.

I accomplish my objects by the mechanism illustrated in the accompanying drawings in which—

30 Figure 1 is a perspective view of the hanger.

Figure 2 is an assembly view showing the hanger upon the pole, and illustrating the manner of attachment when a double drape 35 is used.

Figure 3 is similar to Figure 2 except that it shows the manner of attachment when a single drape is used.

Figures 4 and 5 are perspective views of 40 the principal component elements of the hanger.

Figure 6 is a view showing the assembly of the elements of Figures 4 and 5.

Figure 7 illustrates the snap fastener for 45 use at the bottom of the hanger.

Figure 8 is a perspective view showing a double drapery hanging in a so-called "French plait."

Figure 9 is a sectional view on the line 50 9—9, Figure 8, and

Figure 10 is a plan section on the line 10—10, Figure 9.

Like numerals denote like parts throughout the several views.

55 Referring first to the form shown in Fig-

ures 1 to 7 inclusive, the hanger consists of two principal elements *a* and *b*, which are similar but not identical. They are made preferably of resilient sheet metal, for example, spring brass. The member *a* has a 60 depending flange 4 adapted to lie in the median plane of the device. The flange has an aperture 5. The body 6 is curved to extend upward along one side of the pole, and at the upper end it has a terminal or jaw 65 consisting in the present case of two furcations 8 which are apertured at the upper end as illustrated. In practice this terminal stands approximately on a level with the body of the pole 10. The body also has a 70 branch or strap 12 which passes up over the top of the pole to the opposite side where it has a second terminal 14. According to the design illustrated this second terminal is furcated and provided with two points 75 15 for gripping the drapery. Members *a* and *b* are preferably ribbed as at 18, Figure 1 and elsewhere, but for the sake of clearness these ribs are not depicted in Figures 4, 5 and 6. They tend to stiffen the 80 members and are desirable, but are not essential.

The member *b* is quite similar to member *a* and has a flange 4 at the bottom containing an aperture 5. The body 20 has two up-standing furcations 22 analogous to the furcations 8 of element *a*. They likewise are apertured at the upper end. A branch 24 is similar to the branch 12 and passes up over the top of the pole to the opposite side 90 of the structure where it is provided with a terminal 25 similar to the second terminal provided on the member *a*. This is furnished with points 26 for engaging the drapery. According to the preferred design the 95 branches or straps 12, 24 are arch shaped or flattened, as shown. This causes the hanger to slide much more easily than otherwise, and avoids the need of anti friction rollers.

For ordinary cases the two members *a* and *b* will be permanently fastened together by means of an eyelet 30 which passes through the apertures 5 in the flanges 4 and rigidly holds the two parts assembled. 105 When thus assembled the branch 24 passes through an aperture 32 formed in the body of member *a*, while the branch 12 passes between the furcations 22 of member *b*. The secondary terminals 14, 25 lie on the outside 110

of the furcations 22, 8 respectively, and the prongs face inward toward the apertures on the companion terminals. In practice these prongs will engage, if not actually enter into 5 the apertures formed at the upper end of the furcations 8, 22, although the precise form of the terminals is non essential and may be considerably varied.

- The tension of the spring metal is such as 10 to cause the members *a* and *b* to press outward, which, of course, tends to force the cooperating terminals toward each other. When it is desired to open the gripping jaws—that is, to force the terminals apart, 15 the operator presses together upon the bodies of the two members *a* and *b* as illustrated in Figure 6 and when the pressure is removed, the resilience of the members will force the terminals toward each other or the 20 gripping jaws to close. Furthermore, the tension induced by the weight of the hanger and drapery will increase the gripping action of the jaws; and the heavier the weight, the greater will be the gripping action. 25 Viewed in one aspect, the branches overlying the pole may be regarded as "straps" tending, under stress, to draw the outer jaws or terminals into close contact with the inner ones. According to the present design, this 30 supplements the spring action and may be said to be "self compensating" in the sense that the harder the pull the greater the grip.

- Operation:** Let it be assumed that a double drape is to be hung, as shown in Figure 35 2. The two drapes 36 are passed up along the outside of the hanger, and the upper edges 37 passed down between the cooperating jaws or terminals. The operator, of course, at this time holds the jaws open by 40 pressing inward on the members *a*, *b*, but as soon as the upper edges are thus in place, he releases the members and permits the jaws to engage the fabric. He then brings the two layers of fabric into contact with the 45 flanges 4 after which he inserts the pointed shank 40 of a snap fastener, best shown in Figure 7. The shank is passed through the fabric and through the eyelet 30. It is provided at the outer end with a button 41 and 50 at the inner end with a head 42 adapted to be engaged by the gripping members 43 of a companion button 44. The assembly then appears as shown in Figure 2, and by reference to it will be observed that the drapery 55 conceals not only the pole, but also every portion of the hanger. Nothing appears to an observer except the buttons 41, 44 of the snap fastener, and these may be colored to harmonize with the drapery. 60 If a single drape is to be employed, the end 50 is inserted between the jaws on one side, then a stretch 51 is laid down along the outer side of the device, down to the flanges 5 and around the bottom 65 tom of said flanges and up alongside of

the device to the second jaw or pair of terminals, where a doubled portion 53 is inserted. A stretch 54 of fabric is then led down the outside and brought into contact with the fabric already adjacent to the 70 flanges 4. The balance 55 of the drape is then permitted to hang down in the usual manner. The snap fastener is then passed through three layers of the fabric, as illustrated at the bottom of Figure 3. The result 75 of this manipulation is that the pole and hangers are entirely concealed, although but a single piece of fabric is employed for the drape.

Referring now to Figures 8, 9 and 10, the 80 hanger itself is the same as before, but instead of inserting the snap fasteners through the eyelet 30, a bar 60 passes through the eyelet, said bar having eyes 61 at each end as best shown in Figures 9 and 85 10. In applying the drapery under these conditions a plait 62 is formed by gathering the fabric and bringing it into contact with the two opposite sides of the loop 61. The fabric is then held in place by snap fasteners 90 of the same type as before. These plaits or folds 62 are sometimes referred to in the trade as "French plaits," and the advantage is that they give an appearance of fullness which adds to the appearance of the hanging. It is not usually desirable to form these 95 plaits at the end of the drapery adjacent to the door or window casing, and hence at these points the double eyelet bar 60 will be omitted and the snap fasteners will penetrate directly through the eyelets 30 as in the previously described assemblage. The latter form of assemblage is shown at the left end of Figure 8, while the French plait is depicted at the right end of said figure. 100

From the foregoing it will be observed that by using my type of hanger not only are the pole and the hanger entirely concealed, but the hanger is self-acting in the 105 sense that it grips the drapery and totally dispenses with sewing. The sewing of hangers to draperies, especially where the draperies are of the heavier type, involves much more labor and is a much more difficult operation than would be expected by 110 those not skilled in the art, and for that reason hangers are frequently employed which are self acting but which expose both the pole and the hanger. As a result of my invention, either single or double drapes 115 may be used, and both the pole and hanger will be concealed, and yet sewing is entirely dispensed with. 120

Having thus described my invention what I claim as new and desire to secure by Letters Patent, is:—

1. A hanger for draperies having two members adapted to pass up over the pole from opposite sides, each having a remote terminal at the far side of the pole and also 130

a terminal at the near side of the pole for cooperating with the remote terminal of the opposite member for holding the drapery between them.

5 2. A hanger for draperies having a Y shaped member with resilient sides pressing outward, and means passing over the top of the pole and alongside of the upper ends of the branches of said Y shaped member for 10 clasping the drapery between them.

3. A hanger for draperies comprising members having means at the median plane below the pole for attachment to the drapery, said members passing thence upward along opposite sides of the poles and across the top of it to the opposite side where a terminal is formed, each of said members having a second terminal on the near side of the pole adapted to cooperate 15 with the first mentioned terminal of the companion member for gripping the drapery between them.

4. A hanger for draperies comprising members having means at the median plane below the pole for attachment to the drapery, said members passing thence upward along opposite sides of the pole and having terminals at their upper end, said members also having branches extending 25 across the top of the pole to the opposite side, said branches having terminals at their ends adapted to cooperate with the first mentioned terminals for engaging the drapery between them, the members being resilient for pressing the cooperating terminals toward each other.

5. A hanger for draperies comprising members passing from a point below the pole upward along opposite sides of it and 40 having terminals at their upper end, facing inward, said members also having branches

extending across the top of the pole to the opposite side and beyond the first mentioned terminals, said branches having terminals at their ends lying to the outside of the first 45 mentioned terminals, and said terminals being adapted to engage the drapery between them.

6. A hanger for draperies comprising members having means at the median plane 50 below the pole for attachment to the drapery, said members passing thence upward along opposite sides of the pole and having terminals at their upper end facing inward toward the pole, said members also having 55 branches extending across the top of the pole to the opposite side and beyond the first mentioned terminals, said branches having terminals at their ends lying to the outside of the first mentioned terminals, and the 60 members being resilient and pressing outward to cause the cooperating terminals to press towards each other for engaging the drapery.

7. A hanger for draperies comprising 65 members passing from a point below the pole upward along opposite sides of it and having terminals at their upper end, facing inward, said members also having branches extending across the top of the pole to the 70 opposite side and beyond the first mentioned terminals, said branches having terminals at their ends lying to the outside of the first mentioned terminals, and said terminals being adapted to engage the drapery between 75 them, each of said branches penetrating the opposite member, which has an opening for the purpose.

In witness whereof, I have hereunto subscribed my name.

RAYMOND B. DWYER.
